UNITED STATES PATENT OFFICE.

JOSEPH LANE HANCOCK, OF CHICAGO, ILLINOIS.

DESIGN FOR A BREAST-PUMP.

SPECIFICATION forming part of Design No. 19,593, dated January 21, 1890.

Application filed December 16, 1889. Serial No. 333,984. Term of patent 7 years.

To all whom it may concern:

Be it known that I, JOSEPH LANE HANCOCK, a citizen of the United States, and a resident of Chicago, in the county of Cook and State 5 of Illinois, have invented a certain new and useful Design for a Breast-Pump, of which the following is a specification.

In the accompanying drawings, Figure 1 represents a side elevation of a breast-pump 10 embodying my invention, and Fig. 2 a central vertical section thereof.

The design consists of a cylindrical body A, terminating at the forward end in a cone-shaped breast-plate B and at the rear end in 15 a nipple C, and having a depending bulb D between the ends thereof, the anterior and

posterior walls of which curve upwardly and forwardly from the bottom of the bulb in a generally-inclined direction, the anterior wall joining the body with a long and easy curve ²⁰ just behind the breast-plate, while the posterior wall joins the body with a short and abrupt curve just forward of the nipple.

What I claim as my design, and desire to secure by Letters Patent, is—

A design for a breast-pump, substantially as herein shown and set forth.

JOSEPH LANE HANCOCK.
